ADJUSTABLE WRENCH

Weldon G. Huffman, Chicago, Ill.

Application October 21, 1940, Serial No. 362,136

4 Claims. (Cl. 81—116)

My invention relates to adjustable wrenches, and my main object is to provide a wrench of this type which departs from the heavy or clumsy varieties of adjustable wrenches generally used.

A further object of the invention is to provide a wrench which is light, easily set, and which maintains its hold at all times, and retains exact adjustment until reset.

Another object of the invention is to provide a wrench of the above character which is made with few and simple parts and can therefore be manufactured at low cost.

With the above objects in view and any others which may suggest themselves from the description to follow, a better understanding of the invention may be had by reference to the accompanying drawing, in which—

Fig. 1 is an elevation of one form of the invention;

Fig. 2 is an elevation of a modification of one of the wrench jaws, partly broken away;

Fig. 3 is an elevation of a modified jaw assembly;

Figs. 4, 5 and 6 are, respectively, enlarged sections on the lines 4—4, 5—5 and 6—6 of Fig. 1;

Fig. 7 is a section on the line 7—7 of Fig. 6; and

Fig. 8 is an elevation of a further modification.

Adjustable wrenches may be found in the lighter or heavier forms, but in either case they may be irregular in shape or clumsy to handle; also, they soon develop looseness in the movable jaw, so that the jaws of the wrench do not maintain their hold as adjusted. I have therefore endeavored to depart from these deficiencies by designing a wrench which appears more like a pair of pliers and is balanced in its hold upon the work, whereby to be uniformly adjusted thereon.

In accordance with the foregoing, the novel wrench may be primarily considered as an assembly of two identical units in opposed relation. Each of these units comprises a body member 10 having a diverging shank 11 at one end and a departing handle 12 at the other. The shanks 11 terminate with jaws 13 whose inner faces 14 are parallel for the engagement of the work.

The shanks 11 are slightly cut down from the jaws 13 and the body members 10 as indicated at 15 to be somewhat thinner and define end stops for an elongated band 16 within the end portions of which the shanks 11 are disposed. The band 16 is intended to be slidable along the shanks and act as a cam when advanced to gather the same. For this purpose the shanks are convexed in cross-section as indicated in Fig. 4, and receive correspondingly-shaped formations 16a of the band, which procure the uniform spreading of the jaws when the band is drawn back along the shanks 11 and the uniform gathering of the jaws when the band is advanced.

When the jaws are applied to the work, it is their purpose to become locked in the gripping position, and for this reason both the shanks 11 and the ends of the bands, inside, are formed 5 with meshing ratchet teeth 17 by means of which the jaws are automatically set at the position to which the band is advanced. The band formations 16a are somewhat wider and more spacious in inward direction so as to allow the shanks inward clearance to unmash the teeth 17 and permit the band to slide.

The means of spreading the shanks 11 is in 10 the form of a pair of bow springs 18 which gather rearwardly to be alined by a riveted or otherwise secured band clip 19, then spreading somewhat to terminate along the inner sides of the body members 10 with hooks 20 seating in notches 21 made in such sides. Also, the springs are extended at the sides with clips 21a which have inward bends 21b lodged in side cavities 21c made in the body members. It is the purpose of the hooks 20 to fix the longitudinal positions of the springs 18 identically in relation to the body members 10; and the fastening of the springs at 15 19 enables the hooks 20 to maintain the longitudinal registration of the two major wrench units. The clips 21a firmly secure the springs to the related shanks.

With the wrench applicable as previously described, it is conceivable that the jaws 13 may be gathered to the size of the work and automatically set, the springs 18 and the band 16 maintaining the components of the wrench together and enabling the latter to be handled as a unit for 20 the rotation of the work.

Adjustment is made by applying pressure to the shanks 11 against the tension of the bow springs 18, this permitting the band 16 to be retracted or slid forward along the ratchet teeth. 25 Or, square teeth may be employed as a modification, as shown in Fig. 2. It is however necessary, in order to keep the jaw faces 14 parallel, to lock the divergent handles 12 at the desired size of opening indicated by graduation marks 11a on the shanks 11. For this purpose the handles 12 also receive a band 22 similar to the band 16, and which is effective to spread and gather the handles 12. The band 22 can be locked at any desired spread by crossed double pointed pawls 23 30 attached to the band 22 by a common pivot 24, such pawls cooperating with isosceles tooth racks 25 when the band 22 is moved in either direction.

The pawls 23 may be locked at any desired point of engagement with the tooth racks by a 35 separating clip 26 before the wrench is put into use. The clip 26 is applied across the front of the band 22, having one end passing freely through a slot 22a in one of the band walls to terminate with an enlargement 27, thus forming 40 a hinge; and the other end of the clip is made

with a hook 28 which enters a slot or notch 29 in the inner surface of the other wall of the band. The pawls are thus locked in their engagement with the handle tooth racks 25, and the adjustment of the wrench becomes positively fixed. Yet, the clip can be easily opened by withdrawing the hook 28 from the slot 29 to release the pawls.

The modification of Fig. 3 shows an adaptation of the band 22 and its pawls 23 to the jaw shanks of the wrench. These may be made with tooth racks 11b similar to the tooth racks 25 (or ratchet teeth similar to teeth 17 in Fig. 1). The object of this modification is to dispense with the spring 18, to meet possible demand. Also, a separating locking device on the order of the clip 26 of Fig. 1, may be applied to this modification. Of course, a spring or other suitable separating device may be employed in either case if desired.

The modification of Fig. 8 utilizes the original principle at both ends of the wrench, the object being to make the wrench cover a greater range of sizes, that is, a broader use. In this form two single-ended pawls 30 are provided, these being pivoted at their sources from their respective body members 31, as indicated at 32. The pawls are also pivoted at an intermediate point to each other as indicated at 33. It is my object to adjust the pawls into and out of engagement with tooth racks 34 in the inner faces of the body members 31, so that these may be released when either of the terminal bands 16 are applied to the jaw shanks 11 and then locked when the wrench is to be fixed. The pawls 30 are pivoted directly from the respective members 31 because a band is unnecessary. The unit so formed serves the same essential purpose as the pawls 23 in Fig. 1, that is, to adjust the jaw faces 14 to parallel positions and maintain longitudinal relationship of the body members 31. The pawls 30 are made with longitudinal, intersecting slots 35 and 36 which receive a headed friction rivet 37. Thus, a slight forward push of the rivet, that is, toward the pawl points, serves to gather the pawls and withdraw them from the teeth 34. Then, when the jaws are adjusted to the desired work size, the rivet 33 is pulled back, causing the points of the pawls to become seated in tooth racks 34, at which time friction rivet 31 may have reached the corresponding end portions of the slots 35 and 36.

It will be evident from the above description that I have provided a wrench which is as handy as a pair of pliers yet may be quickly adjusted to the size of the work and locked to the adjusted setting. Thus, when a nut whose size is unknown is to be engaged, the jaws are applied to the nut after the bands 16 and 22 have been placed in retracted position, that is, toward the center of the wrench. Now the band 16 is advanced until the jaws engage the work, after which the band 22 is advanced in rearward direction to bind the handles 12. At this time it may be possible to advance either band another notch or two to the point of imposing a substantial grip on the work. Now the clip 26 is closed and the wrench is set. The wrench requires only the loosening of its pawls to enable it to be drawn off the work, when it can be re-adjusted to different sized work. Further, the wrench is largely made from pairs of identical parts which are simple and easily assembled, rendering the cost of producing the wrench as low as may be consistent with precision and quality. Finally, the novel wrench is

an article which can be easily mastered by any one who is handy with light wrenches or pliers.

While I have described the main embodiment and modifications along specific lines, various minor changes and refinements may be made without departing from their principles, and I desire to consider all such changes and refinements as coming within the scope and spirit of the appended claims.

10 I claim:

1. A wrench comprising a pair of opposed body members, extensions of these in one direction to form jaws and in the other direction to form handles, and means for adjusting the body members to vary the spacing of the jaws and maintain them in parallelism, and other means to resist the contraction of the jaws, such other means comprising a pair of joined springs directed forwardly from a point between the body members 15 to separate and bear outwardly on the respective jaw-forming extensions, the springs having rearward continuations anchored into the respective body members to lock them against relative longitudinal motion.

20 2. A wrench comprising a pair of opposed body members, extensions of these in forward direction to form jaws, extensions of the body members in rearward direction to form handles, means in the zone of the forward extensions to adjust the spacing of the jaws, and a mechanism in the zone of the handles to adjust the spacing thereof, said mechanism comprising a band to limit the spread of the handles, the latter having rows of 25 teeth along their inner surfaces, and a pair of double-pointed pawls centered in the band at a point midway between the handles, said pawls being rockable to engage the teeth of the respective handles and lock the latter in the spread position.

30 3. A wrench comprising a pair of opposed body members, extensions of these in forward direction to form jaws, extensions of the body members in rearward direction to form handles, means in the zone of the forward extensions to adjust the spacing of the jaws, and a mechanism in the zone of the handles to adjust the spacing thereof, said mechanism comprising a band to limit the spread of the handles, the latter having rows of 35 teeth along their inner surfaces, a pair of double-pointed pawls centered in the band at a point midway between the handles, said pawls being rockable to engage the teeth of the respective handles and lock the latter in the spread position, and means to lock the pawls in the rocked position.

35 4. A wrench comprising a pair of opposed body members, extensions of these in forward direction to form jaws, extensions of the body members in rearward direction to form handles, means in the zone of the forward extensions to adjust the spacing of the jaws, and a mechanism in the zone of the handles to adjust the spacing thereof, said mechanism comprising a band to limit the spread of the handles, the latter having rows of 40 teeth along their inner surfaces, a pair of double-pointed pawls centered in the band at a point midway between the handles, said pawls being rockable to engage the teeth of the respective handles and lock the latter in the spread position, and a clip swingable from one wall of the band to close with the other wall thereof at a point between the pawls, whereby to lock the same in the spread position.

45 WELDON G. HUFFMAN.
